US00D786093S

(12) **United States Design Patent** (10) **Patent No.:** **US D786,093 S**
(45) **Date of Patent:** **** May 9, 2017**

(54) **CONTAINER**

- (71) Applicant: **The Gillette Company**, Boston, MA (US)
- (72) Inventors: **Vanessa Christie**, Boston, MA (US); **Andrew Anthony Szczepanowski**, North Attleboro, MA (US)
- (73) Assignee: **The Gillette Company**, Boston, MA (US)

(**) Term: **15 Years**

(21) Appl. No.: **29/538,430**

(22) Filed: **Sep. 3, 2015**

Related U.S. Application Data

- (62) Division of application No. 29/446,055, filed on Feb. 20, 2013, now Pat. No. Des. 740,692.

(57) **CLAIM**

The ornamental design for a container, as shown and described.

DESCRIPTION

FIG. 1 is a perspective view of a container showing my new design, shown in an opened configuration, and with a broken line showing of the environment;

FIG. 2 is a top view thereof;

FIG. 3 is a bottom view thereof;

FIG. 4 is a right view thereof;

FIG. 5 is a left view thereof;

FIG. 6 is a front view thereof;

FIG. 7 is a rear view thereof;

FIG. 8 is perspective view of the container of FIG. 1, but shown in a closed configuration;

FIG. 9 is top view thereof;

FIG. 10 is a bottom view thereof;

FIG. 11 is a right view thereof;

FIG. 12 is a left view thereof;

FIG. 13 is a front view thereof;

FIG. 14 is a rear view thereof;

FIG. 15 is a perspective view of the container of FIG. 1, but without the broken line showing of the environment;

FIG. 16 is top view thereof;

FIG. 17 is a bottom view thereof;

FIG. 18 is a right view thereof;

FIG. 19 is a left view thereof;

FIG. 20 is a front view thereof; and,

FIG. 21 is a rear view thereof.

The dashed broken lines are directed to the environment and are for illustrative purposes only and form no part of the claimed design.

1 Claim, 14 Drawing Sheets
